(57) **CLAIM**

The ornamental design for a lamp, as shown and described.

DESCRIPTION

FIG. 1 is a front, top perspective view of a lamp, showing the new design;

FIG. 2 is a rear, bottom perspective view thereof;

FIG. 3 is a front view thereof; wherein the back, left side, and right side views are identical thereto;

FIG. 4 is a top view thereof; and,

FIG. 5 is a bottom view thereof.

The broken lines of even length shown in the drawings illustrate portions of the lamp that form no part of the claimed design.

1 Claim, 4 Drawing Sheets(56)
